G. G. EARL

MEANS AND METHOD FOR GOVERNING FLUID PRESSURES

Original Filed Aug. 27, 1918

GEORGE G. EARL INVENTOR.

BY Richey Slough + Watts.

HIS ATTORNEY'S

UNITED STATES PATENT OFFICE.

GEORGE G. EARL, OF NEW ORLEANS, LOUISIANA.

MEANS AND METHOD FOR GOVERNING FLUID PRESSURES.

Original application filed August 27, 1918, Serial No. 251,662. Divided and this application filed July 20, 1922. Serial No. 576,260.

My invention relates to means and methods for governing fluid pressures and fluid flows and relates more particularly to the exercise of a control by one fluid pressure, 5 which may be derived from one fluid flow, over a second fluid pressure or flow.

Preventing overreaching and underreaching of controlling mechanisms is one of the objects of my invention.

10 I have found by actual practice that my invention, which relies for its operation upon well known hydrostatic and hydraulic laws, effectively prevents such overreaching and underreaching, and always insures correct and proper automatic control.

Simplicity, rapidity of action and cheapness of construction are other objects of my invention.

These and other objects, as well as the invention itself, may be better understood by reference to the following description of an embodiment of my invention, and which is illustrated in the accompanying drawing.

In the embodiment of my invention illustrated, I apply my invention to systems employing movable surfaces, which may be diaphragms or divisions, and located between two pressures, and which control, through their movements, the operation of fluid or fluid pressure regulating mechanism to maintain equal the pressures applied to such surfaces. In such embodiments I combine with such equal pressure movable surfaces definite amounts of a liquid whose pressure acts on one side thereof, and which liquid is of greater specific gravity than the liquid acting on the other side thereof. The heavier liquid confined in containers so formed and dimensioned and placed to permit not only the maintenance of equal pressures on the two sides of such surface, but will result as well in causing predetermined amounts of motion at such dimensions and in a governing valve for predetermined departures from normal pressure conditions, thereby bringing either constant or slower or more rapid corrective efforts, as may be required. By the use of one or more equal pressure surfaces, which may be divisions or diaphragms operated upon by two or more fluid pressures, due to fluids of different specific gravity, corrective effects are exerted whenever departure from normal ex-

ists. I can also regulate the intensity of the desired corrective effect in any desired relation to the amount of departure from the desired normal condition. 55

In the drawing apparatus is shown whereby through the use of my invention one flow is maintained proportional to another, and different from it by a predetermined amount of pressure. 60

A_2 is a source of fluid pressure and supply, for example, say a water main under pressure, which supplies water through the duct Y_2 to the chamber F_2 , in which there is a restriction D_2 through which the water flows escaping thru a duct W_2 to the outlet of relatively low pressure C_2 . It is evident from what has been said before that the difference between the pressures upon the bottom of the members N_2 and N_2' will be proportional to the differences in pressures on the opposite sides of the orifices D_2 and that such pressures will be conveyed to the bottoms of the diaphragms M_2 and M_2' less the weights of the columns of liquid which are represented by the pressure P_2 . 70

At A_2' is another source of fluid pressure and supply at a lower pressure than the pressure in A_2 , say of water, which flows through the duct Y_2' to the valve chamber V_2 , and thence into the chamber F_2' and through the orifice D_2' therein. Pressure will be conveyed through the duct X_7 to the upper side of the diaphragm M_2 from the approach side of the orifice D_2' and from the discharge side of said orifice through the duct X_8 to the upper side of the diaphragm M_2' . The water flows from F_2' through the valve V_2' and the duct W_2' to the outlet C_2' . The diaphragm M_2 will admit water to the approach side of the restriction D_2' from the source A_2' at a pressure lower than that acting upon the lower side of the diaphragm N_2 by the mercury column P_2 ; that is, the pressure on the approach side of the restriction D_2' will always be equal to that on the approach side of the restriction D_2 less the pressure P_2 . 80

The same thing will be true of the discharge side of the orifice, so that the pressure differences on the two sides of the orifices will always be maintained proportional and the flow from A_2' to C_2' will always be proportional to the flow from A_2 to C_2 . 90

100

105

It will be evident that the diaphragms N_2 and N'_2 may carry regulating valves, or that any two or three or four of said diaphragms could carry regulating valves, and that the 5 mercury columns S_2 and S'_2 may either or both be placed in communication with a container C_2 through the ducts 102 and 104 by the operation of the valves 101, 103 and 105. With these modifications, it will be apparent 10 that not only may the flows be maintained proportional, but that where gas flows are controlled, they may be regulated as to their density.

Assuming the spaces between the pairs of 15 diaphragms N_2 and M_2 and between the diaphragms N'_2 and M'_2 are filled with a relatively heavy fluid, such as mercury, and that communication is had with a container C_2 of preferably relatively large area filled 20 to any level, such as illustrated, with a pressure, such as atmospheric pressure, acting upon its surface, this level being assumed to be as shown, and atmospheric pressure being assumed to be p_1 , the pressure on the top of 25 the diaphragms N_2 and N'_2 will be $h_1 + p_1$, and the pressure on the bottom of the diaphragms M_2 and M'_2 will be $h_2 + p_1$.

Now it will be evident that these relations 30 will exist even though the valves 103 and 105 be subsequently reclosed and that the pressure on the one side of the diaphragms M_2 and M'_2 will still be equal to $h_2 + p_1$, except as this pressure will be altered by the 35 pressure effect exerted on the under sides of the diaphragms M_2 and M'_2 , according to the pressures exerted on the two sides of the orifice D_2 .

Under these conditions, it will be seen that 40 the valves V_2 and V'_2 are controllable to admit and discharge, respectively, more or less fluid from the walls A'_2 to the outlet C'_2 through the intermediate orifice according to the variations in pressure on the two sides of the orifice D_2 as modified by the 45 pressure effects of the intermediate column of trapped heavier liquid between the pairs of diaphragms M_2-N_2 and $M'_2-N'_2$. Thus the flow from the source A'_2 is maintained proportional by a predetermined 50 amount of pressure represented by the pressure effects of the said intermediate liquid columns disposed between the said respective pairs of diaphragms.

It will be seen also that the flows may be 55 gas flows and that in such a case the density of the gas of one flow will be maintained proportional to that of the other flow.

While I have shown a particular embodiment 60 of my invention and the particular details thereof, it will be apparent to those skilled in the art that numerous departures may be made therefrom without departing from the spirit of the invention.

This application is a division from, and 65 continuation of my previously filed co-pend-

ing application Serial No. 251,662, filed August 27, 1918, and in part a re-filing of claims covering certain inventions disclosed therein.

1 claim:—

1. In a fluid system, a conduit adapted to conduct a fluid flow, a second conduit for conducting a second fluid flow, a member responsive to a difference between two opposing pressures and means to communicate two opposing fluid pressures to the said member, one communicated from a point in the said first conduit, the second from a point in the second conduit, and a valve in one of the said conduits adapted to variably restrict the flow therein, under the control of the said member, means to communicate a third pressure adapted to continuously oppose the effect of each of said two opposing pressures. 70 80 85

2. In a fluid system, a conduit adapted to conduct a fluid flow, a second conduit for conducting a second fluid flow, a member responsive to a difference between two opposing pressures and means to communicate two opposing fluid pressures to the said member, one communicated from a point in the said first conduit, the second from a point in the second conduit, and a valve in one of the said conduits adapted to variably restrict the flow therein, under the control of the said member, means to communicate a third fluid pressure adapted to unequally oppose the effect upon said member otherwise accomplished by each of the said communicated pressures. 90 95 100

3. In a fluid system, a first conduit and a second conduit, each of said conduits having restrictions therein, a valve interposed in the second conduit on each side of its restriction, each of said valves being differentially operable by opposing pressures communicated from corresponding sides of the two restrictions. 105

4. In a fluid system, a conduit adapted to 110 conduct a fluid flow, a second conduit for conducting a second fluid flow, a member responsive to a difference between two opposing fluid pressures, means to communicate two opposing fluid pressures to the said member, one communicated from a point in the said first conduit, the second from a point in the second conduit, and a valve in one of the said conduits adapted to variably restrict the flow therein, under the control of the said member, means to communicate a third pressure adapted to oppose one of the said communicated pressures by a predetermined pressure, and to oppose the other communicated pressure by a predetermined different pressure. 115 120 125

5. In a fluid system, a conduit adapted to conduct a fluid flow, a second conduit for conducting a second fluid flow, a member responsive to a difference between two oppos- 130

- ing fluid pressures, means to communicate two opposing fluid pressures to the said member, one communicated from a point in the said first conduit, the second from a point in the second conduit, and a valve in one of the said conduits adapted to variably restrict the flow therein, under the control of the said member, means to communicate a third pressure adapted to continuously 5 modify the effect upon said member by one of the said communicated pressures by a predetermined pressure effect, and to oppose the effect thereon communicated by the other said communicated pressure by a different 10 predetermined pressure effect.

6. In a fluid system, a conduit adapted to conduct a fluid flow, a second conduit for conducting a second fluid flow, a member responsive to a difference between two opposing fluid pressures, means to communicate two opposing fluid pressures to the said member, one communicated from a point in the said first conduit, the second from a point in the second conduit, and a valve in 15 one of the said conduits adapted to variably restrict the flow therein, under the control of the said member, means to communicate a third pressure adapted to continuously 20 modify the effect upon said member by one of the said communicated pressures, by a predetermined pressure effect and to modify by a different pressure effect the effect on said member by the other communicated pressure, said third communicated pressure 25 being a fluid pressure exerted by a head of liquid, said member comprising a pair of movable fluid tight divisions, a chamber between the said divisions, said chamber being filled with a fluid, said two opposing 30 pressures being communicated to the outer sides of said divisions, said third pressure being communicated to the inner side of one of said divisions by said chamber contained fluid.

35 7. In a fluid system, a conduit adapted to conduct a fluid flow, a second conduit for conducting a second fluid flow, a member responsive to a difference between two opposing fluid pressures, means to communicate two opposing fluid pressures to the said member, one communicated from a point in the said first conduit, the second from a point in the second conduit, and a valve in 40 one of the said conduits adapted to variably restrict the flow therein, under the control of the said member, means to communicate a third fluid pressure adapted to continuously 45 modify the effective pressure upon said member effected by one of said communicated pressures and to modify the effect produced thereon by the other communicated pressure by a predetermined differing modifying pressure effect, said member comprising a pair of movable fluid tight 50 divisions, a chamber between the said 55 divisions, said chamber being filled with a fluid, said two opposing pressures being communicated to the outer sides of said divisions, said third pressure being communicated to the inner side of one of said divisions by said chamber contained fluid.

60 8. In a fluid system, a conduit adapted to conduct a fluid flow, a second conduit for conducting a second fluid flow, a member responsive to a difference between two opposing fluid pressures, means to communicate two opposing fluid pressures to the said member, one communicated from a point in the said first conduit, the second from a point in the second conduit, and a valve in one of the said conduits adapted to variably restrict the flow therein under 65 the control of the said member, means to communicate a third pressure adapted to continuously modify the effect upon said member effected by one of the said communicated pressures, and to modify the other communicated pressure effect thereon by a predetermined amount of pressure, said third communicated pressure being a fluid pressure exerted by a head of liquid, said liquid being of different specific gravity 70 than the fluids exerting the said two opposing pressures.

75 9. In a fluid system, a conduit adapted to conduct a fluid flow, a second conduit for conducting a second fluid flow, a member responsive to a difference between two opposing fluid pressures, means to communicate two opposing fluid pressures to the said member, one communicated from a point in the said first conduit, the second from a point in the second conduit, and a valve in one of the said conduits adapted to variably restrict the flow therein under the control of the said member, means to communicate a third pressure adapted to continuously 80 oppose each one of the said communicated pressures but with differing opposing pressure effect upon each, such effects differing by a constant predetermined amount of pressure, said third communicated pressure being a fluid pressure exerted by a head of liquid, said liquid being of different specific gravity 85 than the fluids exerting the said two opposing pressures, said member comprising a pair of movable fluid tight divisions, a chamber between the said divisions, said chamber being filled with a fluid, said two opposing pressures being communicated to the outer sides of said divisions, said third pressure being communicated to the inner side of one of said divisions by said chamber contained fluid.

90 10. In a fluid system, a conduit adapted to conduct a fluid flow, a second conduit for conducting a second fluid flow, a member responsive to a difference between two opposing fluid pressures, means to communicate two opposing fluid pressures to the said member, one communicated from a point in the said first conduit, the second from a point in the second conduit, and a valve in one of the said conduits adapted to variably restrict the flow therein under 95 the control of the said member, means to communicate a third pressure adapted to continuously modify the effect upon said member effected by one of the said communicated pressures, and to modify the other communicated pressure effect thereon by a predetermined amount of pressure, said third communicated pressure being a fluid pressure exerted by a head of liquid, said liquid being of different specific gravity 100 than the fluids exerting the said two opposing pressures.

105 11. In a fluid system, a conduit adapted to conduct a fluid flow, a second conduit for conducting a second fluid flow, a member responsive to a difference between two opposing fluid pressures, means to communicate two opposing fluid pressures to the said member, one communicated from a point in the said first conduit, the second from a point in the second conduit, and a valve in one of the said conduits adapted to variably restrict the flow therein under the control of the said member, means to communicate a third pressure adapted to continuously 110 oppose each one of the said communicated pressures but with differing opposing pressure effect upon each, such effects differing by a constant predetermined amount of pressure, said third communicated pressure being a fluid pressure exerted by a head of liquid, said liquid being of different specific gravity 115 than the fluids exerting the said two opposing pressures, said member comprising a pair of movable fluid tight divisions, a chamber between the said divisions, said chamber being filled with a fluid, said two opposing pressures being communicated to the outer sides of said divisions, said third pressure being communicated to the inner side of one of said divisions by said chamber contained fluid.

120 12. In a fluid system, a conduit adapted to conduct a fluid flow, a second conduit for conducting a second fluid flow, a member responsive to a difference between two opposing fluid pressures, means to communicate two opposing fluid pressures to the said member, one communicated from a point in the said first conduit, the second from a point in the second conduit, and a valve in one of the said conduits adapted to variably restrict the flow therein under 125 the control of the said member, means to communicate a third pressure adapted to continuously modify the effect upon said member effected by one of the said communicated pressures, and to modify the other communicated pressure effect thereon by a predetermined amount of pressure, said third communicated pressure being a fluid pressure exerted by a head of liquid, said liquid being of different specific gravity 130 than the fluids exerting the said two opposing pressures.

2 point in the second conduit, a valve in one of the said conduits adapted to variably restrict the flow therein, under the control of the said member, means to communicate a 5 third pressure adapted to continuously oppose one of the said communicated pressures with a given opposing pressure effect and to oppose the other communicated pressure by a different pressure effect, said third communicated pressure being a fluid pressure exerted by a head of liquid, said member comprising a pair of movable fluid tight divisions, a chamber between the said divisions, said chamber being filled with a fluid, said 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 ed by a head of liquid, said liquid being of different specific gravity than the fluids exerting the said two opposing pressures.

16. In a fluid system, a pair of conduits each adapted to conduct a fluid flow, a pair of fluid flow controlling valve mechanisms each comprising a member responsive to a difference between two opposing fluid pressures, means to communicate two opposing fluid pressures to the said member, one communicated from a point in the said first conduit, the second from a point in the second conduit, a valve in one of the said conduits adapted to variably restrict the flow therein, under the control of the said member, means to communicate a third fluid pressure adapted to continuously oppose one of the said communicated pressures, said third communicated pressure being confined between fluids communicating the said two opposing pressures, said first fluid controlling valve mechanism deriving its two opposing fluid pressures from a first point in each of said pair of conduits, and said second fluid flow controlling valve mechanism deriving its said two opposing fluid pressures from a different point in each of the said pair of conduits.

17. In a fluid system, a pair of conduits each adapted to conduct a fluid flow, a pair of fluid flow controlling valve mechanisms each comprising a member responsive to a difference between two opposing fluid pressures, means to communicate two opposing fluid pressures to the said member, one communicated from a point in the said first conduit, the second from a point in the second conduit, a valve in one of the said conduits adapted to variably restrict the flow therein, under the control of the said member, means to communicate a third fluid pressure adapted to continuously modify the effect of one of the said communicated pressures and to oppose the other communicated pressure, such modification and opposition at all times having the same commensurable relation to each other, said third communicated pressure being a fluid pressure exerted by a head of liquid confined between fluids communicating the said two opposing pressures, said first fluid controlling valve mechanism deriving its two opposing fluid pressures from a first point in each of said pair of conduits, and said second fluid flow controlling valve mechanism deriving its said two opposing fluid pressures from a different point in each of the said pair of conduits.

18. In a fluid system, a pair of conduits each adapted to conduct a fluid flow, a pair of fluid flow controlling valve mechanisms each comprising a member responsive to a difference between two opposing fluid pressures, means to communicate two opposing fluid pressures to the said member, one communicated from a point in the said first con-

duit, the second from a point in the second conduit, a valve in one of the said conduits adapted to variable restrict the flow therein, under the control of the said member, means to communicate a third pressure adapted to continuously modify the said communicated pressures with different pressure forces having a constant difference in pressure values, said third communicated pressure being a fluid pressure exerted by a head of liquid, said liquid being of different specific gravity than the fluids exerting the said two opposing pressures, said first fluid controlling valve mechanism deriving its two opposing fluid pressures from a first point in each of said pair of conduits and said second fluid flow controlling valve mechanism deriving its said two opposing fluid pressures from a different point in each of the said pair of conduits.

19. The process of governing one fluid flow by another fluid flow to maintain it proportional to such other fluid flow and different therefrom by a predetermined amount of pressure comprising communicating the pressures existing on the two sides of a restriction in the line of governing flow to a first and second pressure balancing means respectively, and opposing the effect on each said means by pressures abstracted from the governed fluid flow line at corresponding sides of a restriction therein and in communicating to each of the said means a third source of fluid pressure to modify the resultant effect of pressure communicated to each said means and in throttling the flow in the controlled flow line on the approach and discharge sides of such restriction according to the effect of the pressures upon the balance means and responsive to pressures on the approach and discharge side of the restriction in the governing flow line respectively.

20. In a fluid pressure system, the combination with a conduit conducting a standard fluid flow, a conduit conducting a second fluid flow, a pair of regulating mechanisms, a restriction, said mechanisms being disposed in the line of the second fluid flow on the two sides of the said restriction, said restriction also included in the line of such flow, a restriction in the line of the standard fluid flow, a pair of elements adapted to receive pressures on their two sides, each controlling one of the said mechanisms, the pressure of the fluid at the approach side of the first said restriction being communicated to a side of a first one of the elements, fluid pressure from the discharge side of the first said restriction being communicated to a corresponding side of the second element, fluid pressure from the approach side of the second said restriction being communicated to an opposite side of the said first element, and fluid pressure from the discharge side of the second said restriction being commun- 130

cated to a corresponding opposite side of the second said element, said mechanisms being controllable under the influence of said elements to effect an increase in the rate of flow through the second conduit.

21. In a fluid pressure system, the combination with a conduit conducting a standard fluid flow, a conduit conducting a second fluid flow, a pair of regulating mechanisms, a restriction, said mechanisms being disposed in the line of the second fluid flow on the two sides of the said restriction, said restriction also included in the line of such flow, a restriction in the line of the standard fluid flow, a pair of elements adapted to receive pressures on their two sides, each controlling one of the said mechanisms, the pressure of the fluid at the approach side of the first said restriction being communicated to a side of a first one of the elements, fluid pressure from the discharge side of the first said restriction being communicated to a corresponding side of the second element, fluid pressure from the approach side of the second said restriction being communicated to an opposite side of the said first element, and fluid pressure from the discharge side of the second said restriction being communicated to a corresponding opposite side of the second said element, said mechanisms being controllable under the influence of said elements to effect an increase in the rate of flow through the second conduit, ducts for communicating the fluid pressures on the two sides of the second said restriction to the elements, said ducts comprising a portion filled with a liquid unmixed with the fluid from the first conduit, said fluid exerting a constant difference of pressures in opposite directions upon the said elements and the fluid under pressure communicated from the said first conduit.

22. In a fluid system, a first conduit and a second conduit, each of said conduits having restrictions therein, a valve interposed in the second conduit on each side of its restriction, each of said valves being differ-

tially operable by opposing pressures communicated from corresponding sides of the two restrictions, and means comprising a liquid column, adapted to exert a pressure in opposition to one of the pressures exerted upon one of said valves.

23. In a fluid system, a first conduit and a second conduit, each of said conduits having restrictions therein, a valve interposed in the second conduit on each side of its restriction, each of said valves being differentially operable by opposing pressures communicated from corresponding sides of the two restrictions, and means comprising a liquid column, adapted to exert a pressure in opposition to one of the pressures exerted upon said valves.

24. In a fluid system, a first conduit and a second conduit, each of said conduits having restrictions therein, a valve interposed in the second conduit on each side of its restriction, each of said valves being differentially operable by opposing pressures communicated from corresponding sides of the two restrictions, and means comprising a liquid column, adapted to exert a pressure in opposition to one of the pressures exerted upon one of said valves, and a restriction intermediate the end surfaces of the interposed liquid.

25. In a fluid system, a first conduit and a second conduit, each of said conduits having restrictions therein, a valve interposed in the second conduit on each side of its restriction, each of said valves being differentially operable by opposing pressures communicated from corresponding sides of the two restrictions, and means comprising a liquid column, adapted to exert a pressure in opposition to one of the pressures exerted upon said valves, and a restriction intermediate the end surfaces of the interposed liquid.

In witness whereof, I have hereunto set my hand this 17th day of July, 1922.

GEORGE G. EARL.
